[57] CLAIM

The ornamental design for a pour spout for a can or the like, substantially as shown and described.

DESCRIPTION

FIG. 1 is a rear perspective view of a pour spout for a can or the like showing my new design;

FIG. 2 is a top plan view;

FIG. 3 is a side elevational view, the opposite side being a mirror image thereof; and

FIG. 4 is a rear elevational view.

The broken lines showing a can in FIG. 3 are for the purposes of showing environmental use only.

FIG. 2
